UNITED STATES PATENT OFFICE.

TAGGART ASTON, OF BELLINGHAM, WASHINGTON.

WHARF-WALL AND THE LIKE.

1,392,616.

Specification of Letters Patent.

Patented Oct. 4, 1921.

Application filed March 18, 1921. Serial No. 453,331.

To all whom it may concern:

Be it known that I, TAGGART ASTON, a citizen of the United States, residing at 321 Exchange Building, Bellingham, county of 5 Whatcom, State of Washington, have invented certain Improvements in Wharf-Walls and the like; and I do declare the following to be a full, clear, and exact description of the invention, such as will enable 10 others skilled in the art to which it appertains to make and use the same, reference being had to the figures on the accompanying drawing, which forms a part of this application.

15 This invention relates to improvements in wharf walls and the like. The object of my invention is to provide a form of wharf or quay wall that will consist of two or more horizontally placed relieving platforms together with a combination of small retaining walls stepped down toward the back of the wharf to reduce depth, cost and weight of superimposed filling material on the top of said relieving platforms. Thus requiring 20 less costly or numerous piles and at the same time having the direction of the superimposed load acting downward at right angles to the plane of the horizontally placed relieving platforms in order to reduce lateral 25 pressures on the structure.

30 It is also an object of the invention to provide a form of stepped down bulkhead that will reduce the cost of construction of wharves or quay walls and add to their stability and permanence.

It is also an object to provide a form of wharf wall that will permit the use of concrete as the construction material to compete more closely as to cost with a wharf 35 wall built wholly or partly of timber.

It is also an object to provide a form of wharf wall that will consist of a series of small stepped down retaining walls and relieving platforms in which the small retaining 40 walls also act as girders or abutments to support the relieving platforms next superimposed; and also, by reason of being stepped down in series, to afford a total combined cross sectional area and cost materially less than if only one high retaining 45 wall and one relieving platform had been provided to contain the superimposed filling.

It is also an object to provide a form of bulkhead that will consist of a series of 50 stepped down retaining walls and relieving platforms of reinforced concrete that can be cast or molded in convenient lengths or units

prior to being placed on the substructure or bents, which latter could also be pre-cast for that portion above low water and superimposed and cast or molded to join with the piles after the latter had been placed in position.

I attain these objects with the structure illustrated in the accompanying sheet of drawings in which Figure 1 is a vertical cross section of a preferred form of my wharf, Figs. 2 and 3 are vertical cross sections of optional constructions of the relieving platforms, Fig. 4 is a sectional view of Fig. 3 on the line A—A, and Fig. 5 is a longitudinal, vertical section of an optional form of the relieving platforms.

Similar characters refer to similar parts throughout. More particularly: 1, 1 are the vertical members of the sectional stepped-down bulkhead.

2, 2 are the relieving platforms of said bulkhead.

3, 3 are counterforts strengthening members 1, 1.

4, 4 are longitudinal ribs along the outer edge of platforms 2, projecting upward.

5, 5 are piles driven in the ground beneath floor 12, and may be either of wood or concrete, the latter preferred. These piles are cut off about three feet above low water.

6 is a mound or bulkhead of rubble beneath said wharf and around the feet of piles 5, the ridge of which rises to near low-water mark.

7, 7 are longitudinal ribs on the bottom of relieving platforms 2, 2, projecting downward to engage with notches in bents 8.

8, 8 are the bents of the structure mounted on the heads of piles 5.

9, 9 are longitudinal struts connecting and bracing bents 8. All the members of said structure are preferably made of reinforced concrete.

10 is a concrete or timber sheeting fastened to the inner row of piles and bearing on the rubble bulkhead and butting on the lowest relieving platform 2.

11, 11 are transverse ribs on the lower side of relieving platforms 2 shown in Figs. 2—4.

12 is the wharf floor, preferably of reinforced concrete, built on a fill behind bulkheads 1, 2 and 6, having its front connected to the stepped-down bulkhead 1, 2.

13, 13 are longitudinal strengthening ribs on the lower sides of relieving platforms 2, shown in Figs. 3 and 4.

14 is a transverse strengthening rib on the

lower side of relieving platform 2 shown in Fig. 4.

And 15 is a fill behind bulkheads 1, 2 and 6 and provides support for wharf floor 12.

5 The stepped-down bulkhead is preferably molded in steps consisting of a vertical member 1 and a horizontal member 2.

These steps are mounted in place engaged with bents 8 and bearing on each other.

10 Their surfaces of contact are cemented together with cement grouting. When the several steps are thus mounted and cemented together, a bulkhead is had which not only is well able to resist forces acting landward on the front of the wharf, but also

15 well able to bear the weight of fill 15 and floor 12, together with the load that may from time to time be placed on floor 12.

Lower bents 8 are seated on top of piles

20 5. When said piles are of wood, drift bolts are driven in their heads and molded into said bents. When said piles are of concrete, their reinforcing bars enter said bents. Thus the entire substructure is strongly bound to-

25 gether into a single unit forming an open, light and cheap structure well adapted to resist forces acting against its front as well as those resulting from the weight of fill 15 and the load on floor 12. Pressure from

30 said weight and load is largely born by relieving platforms 2 which passes it vertically downward to the ground through bents 8 and piles 5. And there is relatively but a small component of this force that can act

35 to carry the structure seaward.

What I claim is:

1. In a wharf structure in combination, a wharf floor; a substructure beneath said floor, having vertical members set in the ground; and a stepped-down bulkhead, having horizontal members bearing on said vertical members, engaged with the front of said floor and stepping diagonally downward and shoreward to bear on the ground.

40 2. In a wharf structure in combination; a wharf floor; a substructure beneath said floor, having vertical members set in the ground; a rubble bulkhead on the ground around said vertical members; and a stepped-down bulkhead, having horizontal

45 members bearing on said vertical members, engaged with the front of said floor, and stepping diagonally downward and shoreward to bear on said rubble bulkhead.

50 3. In a wharf structure in combination, a wharf floor; a substructure beneath said floor, having vertical members set in the ground; a rubble bulkhead on the ground around said vertical members; a stepped-

55 down bulkhead, having horizontal members bearing on said vertical members, engaged with the front of said floor, and stepping diagonally downward and shoreward to bear on said rubble bulhead; and a fill behind

said bulkheads adapted to support said 65 floor.

4. In a wharf structure in combination, a wharf floor; a substructure beneath said floor, having vertical members set in the ground; a stepped-down bulkhead, having 70 horizontal members bearing on said vertical members, engaged with the front of said floor, stepping diagonally downward and shoreward to bear on the ground; and a fill behind said bulkhead adapted to support 75 said floor.

5. In a wharf structure in combination; a wharf floor; piling beneath said floor set in the ground; a structure of bents and struts mounted on said piling; a rubble 80 bulkhead on the ground around said piling; a stepped-down bulkhead connected to the front of said floor, stepping diagonally downward and shoreward to bear on said rubble bulkhead, and having horizontal 85 members bearing on said bents; and a fill behind said bulkheads adapted to support said floor.

6. In a wharf structure in combination; a wharf floor; a substructure beneath said 90 floor, having vertical members set in the ground; and a plurality of L-form sections bearing on each other and on said vertical members, adapted to make a bulkhead from the front of said floor, stepping diagonally 95 downward and shoreward to the ground.

7. In a wharf structure in combination; a wharf floor; a substructure beneath said floor, having vertical members set in the ground; a plurality of L-form sections bearing 100 on each other and on said vertical members, adapted to form a bulkhead stepping from the front of said floor diagonally downward and shoreward to the ground; and means to engage said sections with said 105 vertical members.

8. In a wharf structure in combination; a wharf floor; a plurality of piles beneath said floor set in the ground; a bent-and-strut structure mounted on said piles beneath said floor and engaged with said piles; a rubble bulkhead on the ground around said piles; a plurality of L-form sections, bearing on each other and on said bents, adapted to form a bulkhead stepping from 110 the front of said floor diagonally downward and shoreward to bear on said rubble bulkhead; means to engage said sections with said bents; and a fill behind said bulkheads 115 adapted to support said floor.

In witness that I claim the foregoing I have hereunto subscribed my name this 11th day of March, 1921.

120 TAGGART ASTON.
